COMPENSATING SYSTEM

Application filed September 4, 1928. Serial No. 303,814.

This invention relates to means for preserving substantially intact the weight and longitudinal trim of submarine boats.

It is now well known that in order to obtain the required degree of control in the vertical plane when submerged, the buoyancy and fore and aft trim of a submarine when in diving condition must be kept within certain limits, which limits vary with the size and details of design. It is also well known that in order to be efficient in war, a submarine must be capable of passing very quickly from any surface cruising condition to the diving condition. Since the boat must necessarily carry consumables, such for instance as fuel, lubricating oil, fresh water, provisions, etc., the weight must vary from time to time, and so must also the buoyancy, due to variations in the specific gravity of the water of flotation.

Under these circumstances, it is clear that without compensation the amount of water to be taken into the ballast tanks in order to bring the boat into diving condition must be a variable, as must also the longitudinal position of the center of gravity of that water. This delicate and complicated operation, on account of the time necessarily consumed, is not consistent with war efficiency and accordingly it is now the universal practice to provide means for compensation whereby the weight and longitudinal trim of the boat in any surface cruising condition are maintained constant within certain limits. The diving condition is then brought about by filling one or more ballast tanks, usually termed "main ballast". This tankage is, in the submerged condition, completely full, and its volume thus accurately measures, within the limits above referred to, the buoyancy which must be maintained by the compensating system in surface cruising condition. Fuel is by far the most important consumable for which compensation has to be provided.

In order to preserve space, it is now common practice to utilize the space vacated in the fuel tanks by use of fuel for compensating water ballast. In order to avoid mixing the fuel and water and for other good and

sufficient reasons, it is generally considered good practice to keep the fuel tanks when in use completely full and under pressure, the fuel being drawn off from the top, while an equal volume of water is admitted to the bottom.

When the fuel tank top is below the surface water-line, the admission of water may be directly from the sea, but when it is above, the required head is obtained by a pump, usually the same pump as is employed for circulating engine cooling water, since that pump must be in operation when the fuel is being consumed. Now water being heavier than the fuel, it is obvious that the total weight in the fuel tank is increased when fuel is consumed and replaced by water, and in order to compensate for this, according to the present practice, the boat starts out with the necessary amount of compensating water carried in other tankage. The amount of compensating water required to be so carried is, of course, determined by the difference between the specific gravity of the water of flotation and that of the fuel and the total volume of the fuel tanks. As the fuel is consumed, the weight of the system is kept substantially constant by passing overboard an amount of compensating water equal in weight to the difference in weight between the volume of fuel consumed and the equal volume of flotation water which enters the fuel storage tanks, while the fore and aft trim is maintained substantially constant by the suitable fore and aft location of the compensating water tankage with relation to the fuel tanks. In practice, this compensating water tankage is for convenience frequently combined with the auxiliary or adjusting tank or tanks.

The principal objection to the present system just described is that it necessarily involves carrying a substantial weight of compensation water, thus increasing the surface displacement, and decreasing the buoyancy with detrimental effects on seaworthiness and speed. My invention is primarily designed to avoid the necessity for carrying the compensating water above referred to.

Further objects and advantages of my in-

vention will appear from the detail description.

Fig. 1 is a semi-diagrammatic plan view of a submarine boat of known type showing my invention as applied thereto;

Fig. 2 is a section taken substantially on line 2—2 of Fig. 1;

Fig. 3 is a semi-diagrammatic plan view of the stern portion of a submarine boat of known type showing a modified form of my invention as applied thereto.

In general, the essential ballast tanks of any submarine may be divided into three groups. These are the main ballast tank or tanks designated "A" which carry the greater part of the water ballast; the fore and aft trimming tanks designated "B" whose main function is the adjustment of longitudinal trim; and the auxiliary or adjusting tank or tanks designated "C" the center of which is located at or near the center of buoyancy of the boat when submerged. The volume of water carried when submerged in the main ballast tankage "A" is constant, whereas that carried in tankage "B" and "C" is variable.

The total fuel tankage is represented by the three tanks designated D and E. It should be observed that so long as certain conditions specified below are met, the total number of fuel tanks is immaterial, as is also their location in the boat. The volume of tankage E is so proportioned to that of tankage D as to make the total weight, when both are filled with fuel, equivalent to the weight when tankage D is filled with water of flotation and tankage E is empty.

In addition, this tankage is located and proportioned so as to preserve substantial fixity of the longitudinal center of gravity of the system as a whole under all conditions. This tankage is provided with the necessary filling and vent connections, with which this invention is not concerned and which are not indicated on the drawings. The boat illustrated is a known type of twin screw submarine provided with engines G of known type. Between the engines and the fuel tankage D—E are interposed two service and compensating tanks 1 and 1^a. Tanks 1 and 1^a are connected to the engine by a suitable piping system designated generally by 2, which is provided with suitably located valves 3 whereby the tanks can be alternatively connected to the engines for supplying fuel thereto. A U-shaped system of piping 4, provided with two valves 5, connects the service tanks 1 and 1^a. A pipe 6 connects to pipe 4 between valves 5, this pipe having a valve 7. Branch pipes 8 extend from pipe 6 and open into the top of tanks D. A pipe 9, provided with a valve 10 connects to pipe 6 in advance of valve 7 and opens into tank E at the bottom thereof. It will be observed that with this arrangement either tank 1 or

1^a may be employed to serve either one or both engines, while the remaining tank may be completely shut off from the engine supply system and placed in communication with tanks D and E as desired. In addition to the above, sea valves 11, operated by rods 12 and hand wheels 13, are provided for admitting water of flotation to the bottom of tanks D, and any other suitable means, such as a pump, may be employed for supplying water to the tanks D.

Obviously without departing from the spirit of the invention, tanks D may be arranged to function as one tank by fitting suitable conduit connections at the top and bottom thereof, in which case only a single branch pipe 8 would be required.

Tanks 1 and 1^a may be of any desired capacity, but preferably each will be so proportioned as to contain, when full, a weight of fuel not more than the permissible degree of variation in submerged buoyancy. These tanks are provided with the necessary gauges and scales to enable their contents at all times to be accurately determined.

Starting with tankage D and E full of fuel and tanks 1 and 1^a empty, the operation is as follows:—Tanks 1 and 1^a are first filled from tankage E and then shut off from the line 6. One of these tanks, for instance 1, is then placed in communication with one or both engines, while the other, 1^a is shut off therefrom. When 1 is empty, or when any desired amount of fuel has been consumed from it, it is shut off from the engines and 1^a is placed in communication therewith. If the volume of fuel consumed from 1 is represented by V, in order to compensate for the weight expended, a smaller volume of water of flotation must be taken on board, the two volumes in question being in proportion to the specific gravity of the water of flotation and the fuel. To accomplish this compensation and to again make tank 1 ready for the engine supply service, the following procedure is adopted:—1 is now opened to pipes 6 and 8 and it then receives from tankage D a volume of fuel equal to the volume of compensating water required, which compensating water is simultaneously admitted to the bottom of tankage D.

The remaining void in tank 1 is then filled with fuel from tankage E, after which tank 1 is shut off from the line and is ready for use again as an engine service tank, as soon as the desired amount of fuel has been consumed from 1^a. The alternate use of the tanks 1 and 1^a as above described serves to always maintain the weight and longitudinal center of gravity of the fuel system within the required limits. The level of the oil in tankage E is being continuously lowered as the level of the water rises in tankage D and when all the fuel has been passed to the service tanks 130

tankage D is filled with the water of flotation, and tankage E is empty.

Another embodiment of my invention is represented semi-diagrammatically in Fig. 3 where the designations of ballast and fuel storage tanks are identical with those employed in Fig. I. In this second embodiment, the arrangement and proportion of tankage D and E is the same as above described. The top of tankage D is connected to the top of tankage E by valve controlled connections 14. The bottom of tankage D is connected through a valve controlled pipe or conduit 15 to a compensating tank 16, which is also connected to the water of flotation through a valve controlled pipe 17. The bottom of tankage E is connected through a valve controlled conduit or pipe 18 to engine service tanks 19 and 20 which in turn may be alternatively connected to the engines as in Fig. 1. Tanks 16, 19 and 20 are equipped with the necessary gauges and scales to enable the contents thereof to be accurately ascertained.

As before, tanks 19 and 20 may be of any desired capacity, but preferably will have a unit capacity for a weight of fuel not greater than the maximum permissible variation in submerged buoyancy. While tank 16 may be of any desired capacity, it will normally have a capacity bearing the same relation to the unit capacity of 19 or 20 as the specific gravity of the fuel bears to the specific gravity of the water of flotation.

Starting with tankage D—E full of fuel and tanks 19 and 20 empty, the operation is as follows:—Tanks 19 and 20 are first filled with fuel from tankage E and then shut off therefrom, after which either one, for instance 19, is opened to the engines, 20 remaining shut off from the engines for the time being. When 19 is empty, or any desired amount of oil has been consumed therefrom, it is shut off from the engines and 20 is connected therewith. Tank 19 is then refilled with fuel from tankage E and an equivalent weight of water is admitted to tank 16 which is thereafter shut off from the water of flotation. The top connections between tankage D and E being open, the water in tank 16 is forced into the bottom of tankage D replacing an equal volume of oil which passes over into tank E, the effect so far as compensation is concerned being the same as in the embodiment of Fig. 1.

Obviously and without departing from the spirit of the invention, by making the necessary changes in piping connections the separate compensating tank 16 could be dispensed with and its functions could be performed alternatively by the service tanks 19 and 20. The separate compensating tank 16 is the preferred arrangement, however, since in its absence, carelessness in operation might result in a mixture of fuel and water in the service tanks.

While the foregoing description has pur-

posely been limited to compensation for fuel only, it is obvious that the same apparatus can also be employed for compensating for other consumables, such, for instance, as lubricating oil, fresh water and provisions. When the weights of other consumables used bear a fixed and known relation to the weight of fuel consumed in a unit of time or distance, the result is the same as if a fuel of higher specific gravity were used. In order to maintain constant weight, it is only necessary to take on board a correspondingly increased volume of compensating water. When the system is used for the compensation of other consumables in addition to fuel, that is to say, when the compensating water for such other consumables is eventually lodged in the fuel storage tanks, the stowage for such other consumables must be properly positioned with respect to the tankage D—E in order to preserve fore and aft trim or other means must be adopted for the regulation of trim independent of the compensation for weight.

It will be observed that with the system above described, tankage D is always full when submerged, and accordingly need not take the pressure of submersion in the outer walls, which, if desired, can be of light construction provided the inner walls are sufficiently strong to resist the pressure due to submergence.

On the contrary, the contents of tankage E being variable, if this tank is so located as to be exposed to the pressure of submergence, the outer wall must be strong enough to resist that pressure.

In both forms of my invention illustrated, I employ a suitable pump P and appropriate piping, with suitably located valves, for supplying water to the tanks D when on the surface with the upper portions of these tanks above the water of flotation.

While the drawings illustrate a construction where normally the outer walls of D would be non-pressure resisting and the outer wall of E would be pressure resisting, this particular arrangement is by no means essential to the invention. With tankage D arranged as indicated, tankage E might, if desired, be located inside the pressure resisting hull. Also, tankage D might be located inside the pressure resisting hull, in which case, if of weak construction, it would in the submerged condition be shut off from the water of flotation.

What I claim is:—

1. In compensating means for submarine boats, storage tanks for fuel lighter than but not miscible with water, fuel service tanks, means for supplying fuel to said service tanks from the storage tanks, and means for supplying to the storage tanks water equal in weight to the weight of the fuel withdrawn from said storage tanks.

2. In compensating means for submarine boats, storage tanks for fuel lighter than but not miscible with water, means for withdrawing fuel from the tanks in unit quantities, and means for supplying to the fuel storage tanks water equal in weight to the weight of the unit quantity of fuel withdrawn from said tanks.
3. In compensating means for submarine boats, storage tanks for fuel lighter than but not miscible with water, means for withdrawing fuel from certain of said tanks in unit quantities of volume such that the weight of a corresponding volume of water is within the permissible variation in buoyancy of the boat, means for supplying to said certain tanks water equal in volume to the fuel withdrawn therefrom, and means for withdrawing fuel from the remaining fuel tanks.
4. In compensating means for submarine boats, storage tanks for fuel lighter than but not miscible with water, a pair of service tanks, controlled means for supplying fuel from the storage tanks to either of the service tanks, selectively, means for connecting either of the service tanks, selectively, to the engines of the boat, and means for admitting water to the storage tanks.
5. In compensating means for submarine boats, storage tanks for fuel lighter than but not miscible with water, a pair of service tanks, controlled means for supplying fuel from certain of the storage tanks to either of the service tanks, selectively, controlled means for supplying fuel from the remainder of the storage tanks to the other of the service tanks, selectively, means for alternatively connecting the service tanks to the engines of the boat, and means for admitting water to said certain storage tanks.
6. In compensating means for submarine boats, storage tanks for fuel lighter than but not miscible with water, means for withdrawing fuel from the tanks, selectively, and means for supplying water to certain of the tanks in unit quantity, the weight of such unit quantity being within and approximately equal to the permissible variation in buoyancy of the boat.
7. In compensating means for submarine boats, storage tanks for fuel lighter than but not miscible with water, controlled means for withdrawing fuel from certain of said tanks, controlled means for withdrawing fuel from the remainder of the tanks, and means for supplying water to said certain tanks in unit quantity the weight of which is within and approximately equal to the permissible variation in buoyancy of the boat.
8. In compensating means for submarine boats, storage tanks for fuel lighter than but not miscible with water, a pair of service tanks, controlled means for supplying fuel from certain of the storage tanks to either of the service tanks, selectively, controlled means for supplying fuel from the remainder of the storage tanks to either of the service tanks, selectively, means for alternatively connecting the service tanks to the engines of the boat, a water measuring tank, controlled means for admitting water to said measuring tank, and controlled means for supplying the water from the water measuring tank to said certain fuel storage tanks, the volume of the water measuring tank being such that the weight of the water contained therein when full is within and approximately equal to the permissible variation in buoyancy of the boat.
9. The method of compensating for fuel consumed on a submarine boat, consisting in withdrawing the fuel from certain of the storage tanks in predetermined unit quantities only, the volume of this unit quantity being such that the weight of a like volume of water is equal to the weight of the total amount of fuel withdrawn from the storage tanks at one time, and then replacing the fuel withdrawn from certain tanks by an equal volume of water.
- In witness whereof, I hereunto subscribe my name this 8th day of August, 1928.
